PYROLYSIS OF METHANE

Harold M. Smith, Peter Grandone, and
Harry T. Rall, Bartlesville, Okla.

Application April 26, 1934, Serial No. 722,521

2 Claims. (Cl. 260—168)

(Granted under the act of March 3, 1883, as
amended April 30, 1928; 370 O. G. 757)

This invention described herein may be manufactured and used by or for the Government for governmental purposes, without the payment to us of any royalty thereon.

5 This invention relates to the pyrolytic synthesis of aromatic hydrocarbons from natural gas, more especially it is directed to a method for the production of benzene by the pyrolysis of methane.

In their efforts to devise and improve processes 10 for the conversion of natural gas hydrocarbons to commercially valuable products such as light oil (benzene) investigators have been handicapped in obtaining their objective through lack of sufficient information as to conditions necessary for the most efficient treatment. This deficiency arises especially through lack of data 15 concerning the decomposition rates of the hydrocarbon gases. Methane has been particularly neglected in this regard, and thermal decompositions designed to produce light oil (benzene) have been conducted largely on a trial and error basis. We have conducted a systematic pyrolytic 20 study of methane and have ascertained some of the operating conditions necessary when this gas is processed to produce light oil (benzene).

One object therefore of this invention is to provide a method for the production of light-oil (benzene) from methane.

When natural gas hydrocarbons are subjected 30 to the action of heat the simple hydrocarbons are split and "free radicals" are formed. These "free radicals" very quickly recombine in numerous new and different combinations, and these new compounds are also subject to condensation and 35 polymerization reactions so that there finally results from the thermal decomposition a number of different products such as hydrogen, acetylene, ethylene, benzene, naphthalene, anthracene, pyrene and increasingly heavier compounds until the final degradation product, carbon, is obtained. Some of the products are what may be 40 termed primary reaction products in that they are the simplest products that can be isolated in a stable condition; while other products are designated as secondary in that they may be assumed to proceed from the polymerization and 45 condensation reactions of the primary products. Hydrogen, acetylene, and ethylene are examples of the primary products and benzene, naphthalene, and the remainder of the heavy compounds are examples of secondary products. Since the object of this invention is the production 50 of one of the secondary products it is apparent that the time factor is of great importance. In other words if a maximum production of light-oil (benzene) is to be obtained the series of reactions started by the application of heat must proceed far enough so that the primary products are converted to a maximum 55 amount of light-oil (benzene), but these reac-

tions must be stopped before the production of heavy hydrocarbons is increased at the expense of the light-oil (benzene).

We have carried out numerous experiments to determine the decomposition rates for methane at different temperatures. As a result of these experiments we have found a linear relationship between the specific decomposition rate K , expressed in reciprocal seconds, and the reciprocal of the temperature in degrees Kelvin. This relationship is illustrated in Figure 1, where the logarithm of K is plotted against the reciprocal of the temperature in degrees Kelvin, and may be expressed as follows:

$$\log_{10} K = 14.4945 - \frac{19.525}{T} \quad 15$$

In using this equation it is essential that T represent the average temperature of the gases in the cracking zone as closely as it can be determined. This equation is valid over the cracking range of 1000° C. to 1200° C.

We have also discovered that when methane is reacting according to the above equation that the maximum yields of light-oil (benzene) at a given temperature are obtained when only sufficient time is allowed for approximately 25 percent by weight of the methane to be decomposed.

In accordance with these discoveries when methane is processed to produce the maximum amount of light-oil (benzene) at a certain temperature at atmospheric pressure the time θ which a given particle of gas should remain in the reaction tube is given by the following equation which results from combining these two discoveries and expressing them in the logarithmic form:

$$\log_{10} \theta = \frac{19.525}{T} - 15.0967 \quad 30$$

wherein the contact time in seconds is represented by the Greek letter theta. 40

For example, if it is desired to determine the contact time necessary to process methane for maximum light-oil (benzene) yield at 1150° C. then according to the above equation, since 1150° C. = 1423° K., we have

$$\log_{10} \theta = \frac{19.525}{1423} - 15.0967 \quad 35$$

$$= -1.3767 \quad 50$$

then

$$\theta = .042 \text{ second} \quad 60$$

Coming now to a more detailed description of the process, reference is made to Figure 2 which is a diagrammatic drawing in elevation of an assembly of apparatus suitable for the conduction of thermal decomposition. The gas supply, methane, enters the system at 1 and passes through the measuring devices 2 into the crack-

ing chamber 3. This chamber may consist of a single tube, or of several lengths of tubing arranged in parallel or even as a coil, but regardless of its arrangement the gas must enter at such a rate that it will remain in the heated portion, at the temperature used, the proper time as determined by the equation

$$\log_{10}\theta = \frac{19,525}{T} - 15.0967$$

10 The gas leaving the cracking tube should now contain the maximum amounts of light-oil (benzene) that can be produced from methane by a one stage process at the temperature employed 15 and at atmospheric pressure.

In conclusion the gas containing the light-oil (benzene) vapors may now be subjected to appropriate scrubbing and recovery methods 4 for which the usual commercial equipment is suitable. In fact the entire process may be carried out in equipment that conforms to the usual commercial practices, the only criterion being that the cracking unit have the proper volume 20 to provide a contact time in accordance with the previously cited equation.

Having described our invention, what we claim as new and wish to secure by Letters Patent is:

1. A process for the pyrolytic conversion of methane into benzene, consisting in limiting the

methane decomposition to approximately 25 percent by weight for any temperature within the temperature range of 1000° C.-1200° C. by passing the gas through a reaction tube at any temperature between 1000° C.-1200° C. at atmospheric pressure and at a time interval expressed by the formula

$$\log_{10}\theta = \frac{19,525}{T} - 15.0967$$

10 wherein the contact time in seconds is represented by the Greek letter theta.

2. A one stage pyrolytic process for obtaining an optimum yield of benzene from methane with- 15 in a temperature range of 1000° C.-1200° C., consisting in limiting the methane decomposition to 25 percent by weight by passing the gas through a reaction tube at any temperature between 1000° C.-1200° C. at atmospheric pressure and at a time interval expressed by the formula

$$\log_{10}\theta = \frac{19,525}{T} - 15.0967$$

20 wherein the contact time in seconds is represented by the Greek letter theta.
